(57) **CLAIM**

The ornamental design for an adjustable light as shown and described.

DESCRIPTION

FIG. 1 is a perspective view of an adjustable light.

FIG. 2 is an enlarged view of a portion of the adjustable light of FIG. 1 taken from within callout 2--2.

FIG. 3 is a left-side view of the adjustable light of FIG. 1.

FIG. 4 is an enlarged view of a portion of the adjustable light of FIG. 3 taken from within callout 4--4.

FIG. 5 is a right-side view of the adjustable light of FIG. 1.

FIG. 6 is an enlarged view of a portion of the adjustable light of FIG. 5 taken from within callout 6--6.

FIG. 7 is a front view of the adjustable light of FIG. 1.

FIG. 8 is an enlarged view of a portion of the adjustable light of FIG. 7 taken from within callout 8--8.

FIG. 9 is a rear view of the adjustable light of FIG. 1.

FIG. 10 is an enlarged view of a portion of the adjustable light of FIG. 9 taken from within callout 10--10.

FIG. 11 is a top view of the adjustable light of FIG. 1; and, FIG. 12 is a bottom view of the adjustable light of FIG. 1. The dash-dash broken lines shown in the drawings depict portions of the adjustable light that form no part of the claimed design. The dash-dot broken lines shown in the drawings are for annotating the enlarged views and form no part of the claimed design.
